UNITED STATES PATENT OFFICE.

GEORGE B. WEBB, OF WESTFIELD, NEW JERSEY, ASSIGNOR TO WYCKOFF, SEAMANS & BENEDICT, OF ILION, NEW YORK, A CORPORATION OF NEW YORK.

TYPE-WRITING MACHINE.

SPECIFICATION forming part of Letters Patent No. 784,366, dated March 7, 1905.

Application filed September 1, 1903. Serial No. 171,508.

To all whom it may concern:

Be it known that I, GEORGE B. WEBB, a citizen of the United States, and a resident of Westfield, in the county of Union and State of New Jersey, have invented certain new and useful Improvements in Type-Writing Machines, of which the following is a specification.

My invention relates to type-writing machines, and more particularly to means for arresting the leading edge of the paper as it is introduced into the machine, so that the paper may always be started at the same point and properly squared and entered into the machine.

To the above and other ends, which will hereinafter appear, my invention consists in the features of construction, arrangements of parts, and combinations of devices to be hereinafter described, and particularly pointed out in the appended claims.

In the accompanying drawings, wherein like reference characters indicate corresponding parts in the various views, Figure 1 is a top view, with parts omitted and parts broken away, of one form of type-writing machines embodying my invention. Fig. 2 is a detail fragmentary perspective view, with parts broken away, of the paper feeding and arresting devices. Fig. 3 is a detail fragmentary perspective view of the paper-apron. Fig. 4 is a fragmentary end elevation, with parts in section, of sufficient of the machine to illustrate my invention, the view illustrating the disposition of the parts when the feed-rolls are thrown out of operation and the paper is introduced. Fig. 5 is a like view of the same, showing the disposition of the parts when the paper is clamped in position by the feed-rolls.

While I have illustrated my invention applied to a "front-strike" type-writing machine, it should be understood that the invention may be applied to various characters of writing-machines and that numerous changes may be made to facilitate such application.

The top plate 1 of the machine is open at the front portion thereof, as indicated at 2, to enable the type-bars (not shown) to strike upwardly and rearwardly at the front portion of the platen 3.

The platen is mounted to rotate in a swinging platen-frame 4, pivoted at 5 to a truck 6, that is supported upon suitable bearing-rollers which coöperate with tracks on a fixed plate 8, said plate being supported upon upwardly-extending supports 9, which project from the top plate. A line-spacing lever 10 is pivoted at 11 to the carriage, and a finger or projection 12 on said lever coöperates with an upwardly-projecting link 13, that carries a line-spacing pawl 14, which coöperates with the line-spacing ratchet-wheel 15, secured to the platen. A rock-shaft 16 extends from side to side of the platen-frame and is mounted in bearings in the ends thereof, and projecting upwardly from said rock-shaft is a crank-arm 17, provided with a finger-piece 18. A paper-apron 19 extends at its upper edge from a point at the rear of the platen to the front edge of the apron where it is adjacent to the platen, and the paper-apron conforms generally at a portion thereof to the contour of the platen. This paper-apron is provided with apertured studs 20 on the rear side thereof which receive the rock-shaft 16, which passes loosely therethrough and supports the paper-apron in place. The paper-apron is apertured at different points 21 throughout the length thereof to enable the paper-feed rollers 22 to extend into the openings and to bear against the face of the platen, as indicated in Fig. 5. The paper-feed rollers are mounted on a shaft 23, supported in lugs or bearings 24 on depending rigid arms or hangers 25. These arms are curved and provided with bearing edges 26 at the upper ends thereof, which are received in V-shaped grooves or recesses 27 at the rear face of the cross-bar 28 of the platen-frame, so that the bearing edge 26, with its bearing-groove, affords a pivotal center on which the arms 25 are adapted to swing. Each of the arms 25 is apertured at 29 and is adapted to receive a screw 30, which projects freely therethrough and is received at its forward end in a threaded opening in the bar 28 of the platen-frame, to which it is secured. A coiled expansion-spring 31 surrounds each screw 30 and bears at one end against the associated hanger 25 and at its opposite end against a

thumb-nut 32, that is threaded on the screw, so that the springs maintain the edges 26 on the hangers seated in their bearings in the platen-frame.

5 From the foregoing description it will be understood that simple and efficient means are provided for readily mounting the supports for the feed-rollers in place and for removing them when desired and that by turning the 10 platen-frame back the pressure of the springs 31 on the feed-rollers may be varied at will. In order to disconnect the feed-roller supports from the platen-frame, it is merely necessary to entirely remove the nuts 32 and the springs 15 31 from the screws 30, when the feed-rollers and their supports or hangers may be removed as an entirety from the machine. Projecting rearwardly from the rock-shaft 16 are fingers 33, each of which coöperates with a 20 stud 34, projecting from an arm or hanger 25. When a rearward pressure is exerted upon the finger-piece 18, the fingers 33 will deflect the paper-feed-roller hangers against the tension of their springs and the feed-rollers will 25 be moved to the position represented in Fig. 4. Adjacent to the feed-rollers and situated forward of the point where the feed-rollers contact with the platen is a series of fixed paper stops or lugs 35, which project upwardly 30 toward the platen and are secured to the face of the paper-apron, so that they remain at a fixed or substantially fixed distance from and are never brought into contact with the platen. These paper-stops are alined longitudinally 35 of the platen and extend throughout the length of the paper-apron, so that they are adapted to coöperate with either wide or narrow sheets of paper or small strips or cards.

When I refer herein to a "fixed" paper-stop, 40 I mean a stop which is not moved in order to remove it from or to interpose it in the path of the leading edge of the paper.

From an inspection of Fig. 4 it will be observed that when the paper-feed rollers are 45 moved to the inoperative position the paper-stops 35 are adapted to arrest the leading edge 36 of the paper 37 when it is introduced into the machine and that the paper may always be started at the same position in the machine 50 and may be properly squared by the paper-stops as the paper is introduced and without the necessity of relying upon the judgment of the operator to determine whether or not the paper is properly positioned in the machine. When 55 pressure upon the finger-piece 18 is removed, the parts will assume the positions shown at Fig. 5, with the paper-feed rollers 22 bearing against the paper. During the movement of the feed-rollers from the position shown in 60 Fig. 4 to that shown in Fig. 5 they will bear against the paper and move the leading edge thereof out of contact with the paper-stops 35 and will press it against the platen so that the paper is free to be fed in the direction of its 65 line-spacing movements. It will be observed

that the paper is not disturbed from the position in which it is set by the movement of the paper-feed rollers back to the operative position, and when they arrive at such position they will firmly press the paper against the 70 platen ready to assist in feeding the paper.

A paper-table 38 is in substantial alinement with the paper-apron, so that the paper passes from the paper-table to the apron in its introduction into the machine. The paper-apron 75 in addition to being loosely supported upon the rock-shaft 16 is held against vibration thereon by a spring-rod 39, which is secured at one end, 40, to the rear bar 28 of the platen-frame and at its opposite end, 41, to the rear 80 side of the paper-apron.

It will be seen that while the paper-feed rollers are in position to coöperate with the paper to feed it the paper cannot reach contact with the stops 35, so that they are only 85 effective to arrest the leading edge of the paper when the rollers are moved out of contact with the platen. By reason of the fact that the paper-feeding devices or feed-rollers 22 are in advance of the paper-stops, considered 90 with relation to the point of insertion of the leading edge of the paper or in the direction of the line-feed of the paper, the feed-rollers are adapted when restored to the normal position to force the paper away from the stops 95 and into contact with the platen without disturbing the arrangement of the paper attained with the aid of the stops.

The stops extending, as they do, at various points throughout the length of the paper-apron, which is substantially equal to the length of the platen, are adapted to coöperate with narrow or wide sheets of paper or cards of varying widths, and for this reason it is preferred to have the stops at various points 100 throughout the length of the platen, though obviously this need not be the case. Instead of a number of separate stops a single stop of sufficient length may be employed, and various other changes may be made without departing 105 from the spirit of my invention.

Certain of the features shown in the accompanying drawings form no part of my present invention, but are claimed in a separate application filed herewith. 115

What I claim as new, and desire to secure by Letters Patent, is—

1. In a type-writing machine, the combination of a fixed paper-stop for arresting the leading edge of the paper, and means for forcing the paper away from the stop after the paper is arrested thereby. 120

2. In a type-writing machine, the combination of a fixed paper-stop adapted to arrest the leading edge of the paper, a paper-feeding device, and means for moving said paper-feeding device into and out of operative position, the construction and arrangement of the parts being such that the leading edge of the paper is adapted to be arrested by said stop when the 125 130

paper-feeding device is in the inoperative position.

3. In a type-writing machine, the combination of a fixed paper-stop adapted to arrest the leading edge of the paper, a paper-feeding device, and means for moving said paper-feeding device into and out of operative position, the construction and arrangement of the parts being such that the leading edge of the paper is adapted to be arrested by said stop when the paper-feeding device is in the inoperative position and the act of moving the paper-feeding device to the operative position is effective to release the paper from said paper-stop.

15 4. In a type-writing machine, the combination of a platen, a fixed paper-stop and a paper-feeding device forward of the paper-stop and which is adapted to move the paper away from the stop and into contact with the platen, and hand-operated means for moving said paper-feeding device.

25 5. In a type-writing machine, the combination of a platen, a paper-apron, a paper-stop carried thereby, a paper-feeding device between the paper-stop and the point where the paper is introduced and which is adapted to move the paper away from the stop and into contact with the platen, and means for moving said paper-feeding device.

30 6. In a type-writing machine, the combination of a platen, a paper-apron which extends substantially throughout the length of the platen, alined paper-stops which are carried by said paper-apron and which extend therefrom at various points throughout the length thereof, a paper-feeding device located forward of the stops, considered with relation to direction of line-feed of the paper, and hand-operated means for moving said paper-feeding device into and out of contact with the platen and for moving the paper away from said stops and into contact with the platen.

45 7. In a type-writing machine, the combination of a platen, an apertured paper-apron which extends substantially throughout the length of the platen, alined paper-stops which project from the face of said paper-apron adjacent to the apertures therein, and which extend at various points throughout or substantially throughout the length thereof, paper-feeding rollers located forward of the stops considered with relation to direction of line-feed of the paper, and hand-operated means for moving said paper-feeding rollers into and out of contact with the platen and for moving the paper away from said stops and into contact with the platen.

50 8. In a type-writing machine, the combination of a platen, a fixed paper-apron, and a stop fixed to and projecting from the face of the paper-apron and adapted to arrest the leading edge of the paper.

55 9. In a type-writing machine, the combination of a platen, a paper-apron, a stop fixed

to and projecting from the face of the paper-apron and adapted to arrest the leading edge of the paper, and means for moving the leading edge away from and out of contact with said fixed stop.

65 10. In a type-writing machine, the combination of a platen, a paper-apron, a stop fixed to and projecting from the face of the paper-apron and adapted to arrest the leading edge of the paper, and a paper-feed roller that is adapted to be moved into and out of contact with the platen and to move the leading edge of the paper away from and out of contact with said fixed stop.

70 11. In a type-writing machine, the combination of a platen, a paper-apron, a portion of which conforms generally to the contour of the platen and which receives the paper and guides it to the platen, a paper-stop which is fixed to and projects from the face of the paper-apron toward said platen and is adapted to arrest the leading edge of the paper, and coöperating paper-feeding devices.

75 12. In a type-writing machine, the combination with a platen, of a fixed paper-stop that is at all times out of contact with the platen and is adapted to arrest the leading edge of the paper.

80 13. In a type-writing machine, the combination with a platen, of a fixed paper-stop that is at all times out of contact with the platen and is adapted to arrest the leading edge of the paper, and a paper-feeding device that is adapted to move the leading edge of the paper away from the paper-stop and to press the paper against the platen.

85 14. In a type-writing machine, the combination of a platen, a fixed apertured paper-apron, a series of fixed stops secured to said paper-apron and at all times out of contact with the platen and adapted to arrest the leading edge of the paper, paper-feed rollers that project through the apertures in said paper-apron and which are adapted to move the leading edge of the paper away from the paper-stops and to press it against the platen, and means for moving the paper-feed rollers into and out of contact with the platen.

90 15. In a type-writing machine, the combination of a platen, a coöperating paper-feed roller, a pivoted paper-feed-roller hanger having a perforation therein, a screw that extends loosely through the perforation in said hanger, a thumb-nut on said screw, and a spring interposed between said thumb-nut and hanger.

95 16. In a type-writing machine, the combination of a platen, a coöperating paper-feed roller, a pivoted detachable paper-feed-roller hanger having a perforation therein, a screw that extends loosely through the perforation in said hanger, a removable thumb-nut on said screw, and a spring interposed between said thumb-nut and hanger, whereby an adjustment of said thumb-nut affords a variation in

the pressure of the spring on said hanger and a removal of the thumb-nut affords a removal of the hanger.

17. In a type-writing machine, the combination of a platen, a platen-frame having a bearing, a feed-roll hanger that is pivoted and bears loosely in the bearing of the platen-frame, a paper-feed roller carried by the hanger, and a spring that retains said hanger in place in its bearing and exerts a pressure to maintain the feed-roller in contact with the platen.

18. In a type-writing machine, the combination of a platen, a platen-frame having a substantially V-shaped bearing or recess therein, a feed-roll hanger that has an end which is loosely seated in the bearing of the platen-frame and provides a pivotal connection on which the hanger swings, a paper-feed roller carried by the hanger, and a spring that retains said hanger in place in its bearing or recess and exerts a pressure to maintain the feed-roller in contact with the platen.

19. In a type-writing machine, the combination of a platen, a platen-frame having a substantially V-shaped bearing or recess therein, a perforated feed-roll hanger that has an end which is loosely seated in the bearing of the platen-frame and provides a pivotal connection on which the hanger swings, a paper-feed roller carried by the hanger, a screw that passes freely through the perforation in the hanger, a thumb-nut on the screw, and a spring interposed between the thumb-nut and hanger.

20. In a type-writing machine, the combination of a platen, a platen-frame having a substantially V-shaped bearing or recess therein, a perforated feed-roll hanger that has an end which is loosely seated in the bearing of the platen-frame and provides a pivotal connection in which the hanger swings, a paper-feed roller carried by the hanger, a screw that passes freely through the perforation in the hanger and takes into a threaded opening in the platen-frame, a removable thumb-nut on the screw, and a coiled spring surrounding said screw and interposed between the thumb-nut and hanger, whereby an adjustment of the thumb-nut affords a variation in the pressure of the spring on the hanger and a removal of the thumb-nut affords a removal of the hanger and feed-roll.

21. In a type-writing machine, the combination of a platen, a paper-feeding device, and a paper-stop that is at all times maintained out

of contact with the platen and against which the leading edge of the paper is adapted to abut when the paper-feeding device is thrown out of coöperative relation with the platen; the construction and arrangement being such that when the paper-feeding device is released to coöperate with the platen, it carries the paper away from the stops and against the surface of the platen.

22. In a type-writing machine, the combination of a platen, a paper-stop that remains at a fixed distance from the platen and against which the leading edge of the paper is adapted to abut, and means for rendering the stop effective to arrest the leading edge of the paper and to force the paper out of contact with said stop.

23. In a type-writing machine, the combination of a platen, a paper-stop that remains at a fixed distance from the platen and against which the leading edge of the paper is adapted to abut, and a paper-feeding device that is adapted to determine when the paper-stop may be employed to arrest the leading edge of the paper.

24. In a type-writing machine, the combination of a platen, a paper-stop that remains at a fixed distance from the platen and against which the leading edge of the paper is adapted to abut, and a paper-feeding device that is adapted to determine when the paper-stop may be employed to arrest the leading edge of the paper and which is also operative to effect a disengagement between the paper and stop.

25. In a type-writing machine, the combination of a platen, a paper-stop that remains at a fixed distance from the platen and against which the leading edge of the paper is adapted to abut, and a paper-roller which is movable to and from operative position and exposes the stop for coöperation with the leading edge of the paper when the said roller is thrown back to the inoperative position and is effective to move the paper from coöperation with the stop when said roller moves to coöperative relation with the platen.

Signed at the borough of Manhattan, city of New York, in the county of New York and State of New York, this 18th day of August, A. D. 1903.
